UNITED STATES PATENT OFFICE.

VICTOR SILVA SACAVEM, OF NEW YORK, N. Y.

TOY WHISTLE.

1,039,814.

Specification of Letters Patent.

Patented Oct. 1, 1912.

Application filed April 10, 1912. Serial No. 689,735.

To all whom it may concern:

Be it known that I, VICTOR S. SACAVEM, a citizen of Portugal, residing at New York, in the county of New York and State of New York, have invented certain new and useful Improvements in Toy Whistles, of which the following is a specification.

This invention relates to improvements in toy whistles and has for its object to provide a device of this nature which while in operation will produce a continuous whistling sound.

With the above and other objects in view I have invented the device illustrated in the accompanying drawings in which,

Figure 1 is an elevational view of my improved whistle, Fig. 2 is a longitudinal sectional view thereof, and Fig. 3 is an end view thereof.

Like reference characters indicate like parts throughout the specification and in the several views in the drawings in which—

1 and 2 indicate whistles each of which is composed of a pair of concave convex plates 3 and 4 having openings 10 in the centers thereof and projecting flanges 5 and 6, the flanges 5 on the members 3 being wider than the flange 6 and adapted to bend over said flange 6 and the edges 7 of the bellows 8 which member connects the two whistles 1 and 2. Interposed between the two whistles and within the bellows is a spring 9 which is adapted to hold the bellows normally expanded as indicated in full lines in Fig. 1 and Fig. 2.

By holding the device between the thumb and fingers of the hand and pressing thereagainst it may be collapsed as indicated in

dotted lines in Fig. 1 thereby forcing the air within the bellows through the whistling members causing a whistling sound and when the pressure against the member is released the spring will cause the device to expand, drawing air in through the whistling members, thus producing a whistling sound and while the device is being operated causing a continuous whistling.

Various modifications and changes may be made in my device without departing from the spirit of the invention.

However, that which I desire to procure by Letters Patent is:

1. A device as described consisting of a plurality of musical members, a bellows for connecting said members and means for holding said members normally expanded.

2. A musical toy consisting of a whistling member having a bellows connected therewith, a spring adapted to hold said bellows normally expanded, and an additional whistle on the opposing end of said bellows.

3. A musical toy consisting of a whistling member having a bellows connected therewith, a spring adapted to hold said bellows normally expanded, an additional whistle on the opposing end of said bellows, and said whistling members having projecting flanges by means of which said bellows is connected thereto.

In testimony whereof I affix my signature in presence of two witnesses.

VICTOR SILVA SACAVEM.
